CLAIM

The ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof; and,

FIG. 9 is front view thereof, showing the lower main body separated from the upper body.

The bracket in FIG. 9 indicates the association of elements of the lower main body being separated from the upper main body and forms no part of the claimed design. The dash-dot broken line in FIG. 9 indicates the path along which the lower main body is separated from the upper main body and forms no part of the claimed design. The evenly spaced broken lines immediately adjacent to the claim, encompassing unshaded regions, represent the bounds of the claimed design while all other broken lines are directed to environment and are for illustrative purposes only; the broken lines form no part of the claimed design.
